UNITED STATES PATENT OFFICE.

ARTHUR J. WIDMER, OF WEBSTER GROVES, MISSOURI, ASSIGNOR, BY MESNE ASSIGNMENTS, TO WIDMER ENGINEERING COMPANY, OF ST. LOUIS, MISSOURI, A CORPORATION OF MISSOURI.

PROCESS OF ERECTING RIBBED CONCRETE FLOORS.

1,291,324.

Specification of Letters Patent. Patented Jan. 14, 1919.

Application filed November 13, 1916. Serial No. 131,017.

To all whom it may concern:

Be it known that I, ARTHUR J. WIDMER, a citizen of the United States, and a resident of Webster Groves, in the county of St. Louis and State of Missouri, have invented a new and useful improvement in Processes of Erecting Ribbed Concrete Floors, of which the following is a specification.

This invention relates particularly to the centering and forms for the floors of buildings of several stories in height, and has for its objects to permit the floor forms to be used over and over without delaying the erection of the building. Further objects are to so arrange the centering for supporting the forms as to permit rapid erection and easy removal of the forms apart from the centering.

The invention consists in supporting the floor ribs on stiff soffit supports; which in turn are supported at their ends on the beam forms, and in supporting the slab portions of the floor on hollow wood forms or pans of suitable shape to form the sides of the ribs and under surface of the floor slab, these forms being supported at their ends and removable in advance of the soffit supports.

Further objects and details of the invention appear in the following description of several embodiments thereof, reference being had to the accompanying drawings.

In the drawings, wherein the same reference characters are used to designate the same parts appearing in the several views,

Figure 1 is a sectional view of a ribbed concrete floor with all supports and forms in place, the section being taken parallel to a rib;

Fig. 2 is a bottom plan view of the same, showing the supports for the form work in cross-section on the line 2—2 in Fig. 1;

Fig. 3 is a cross-section of the floor and forms on the line 3—3 in Fig. 1, looking in the direction of the arrows;

Fig. 4 is an enlarged view similar to Fig. 1, showing a modified form of construction;

Fig. 5 is a cross-section of the construction shown in Fig. 4, on the line 5—5 in Fig. 4 looking in the direction of the arrows;

Fig. 6 is another cross-section of the same,

on the line 6—6 in Fig. 4 looking in the direction of the arrows, the section changing to the right of the break to the line 6—6^a, parts of the form work being broken away to uncover parts behind;

Fig. 7 is a view similar to Fig. 6, showing another form of construction;

Fig. 8 is a view similar to Fig. 4, showing the form of construction shown in Fig. 7; and

Fig. 9 is a cross-section of a shallow rib, showing how forms for a deep rib can be utilized for ribs of lesser depth.

The ribbed floor shown in the drawings consists of a thin slab 10 of concrete having ribs 11 on its under side integrally formed therewith. The finished floor is supported on walls 12 and on intermediate beams 13. The lower edges of the ribs 11 are supported during construction on soffit members 14 which have considerable stiffness and are in turn supported at their ends on the beam forms 15 and stringers 16. The beam forms and stringers are supported on vertical posts 17 which rest upon sets of wedges 18 and blocks 19 supported by the floor beneath. The middles of the soffit members 14 are supported on joists 20, which are held up by inclined struts 21, the lower ends of which diverge and are supported by wedges 22 from the blocks 19.

The sides of the ribs 11 and under surface of the floor are supported by pan shaped forms 23 which are arranged between the soffit members 14 and are supported near their ends by cleats 24 nailed to the sides of the soffit members. In the structure shown in Figs. 1, 2 and 3 of the drawings the pan forms 23 have vertical ends and slightly inclined sides, and are arranged to span the floor space from the side wall 12 or beam 13 to the middle cross rib 25.

The pan forms 23 can be adjusted vertically with respect to the soffit members by nailing the cleats 24 to the soffit members at the proper height, and thereby the depth of the ribs 11 can be varied. The depth of the ribs may also be varied by inserting additional soffit boards 26, supported upon the soffit members 14 by suitable blocks 27, as shown in Fig. 9. Thus the pan forms 23

may be utilized for floors of different thickness and depth of rib.

The concrete in the thin floor slab sets rapidly and the pan forms 28 may be removed 5 a day or two after the concrete has been poured without danger of collapse. By removing the cleats 29, the pan forms may be lowered without disturbing the posts 17 and struts 21, which have to be left in place for supporting the beam forms and soffit members until the concrete has attained enough strength for the floor to be self-supporting. Thus the pan forms are quickly made available for use in constructing the upper floors 15 of the building, and only one set of pan forms is needed for all of the floor.

The construction illustrated in Figs. 4, 5, and 6 is similar in the general arrangement of the centering and forms to that shown in Figs. 1, 2 and 3. The pan forms 28 in Figs. 4, 5 and 6 have inclined ends as well as inclined sides, and are supported at their ends 29 by means of cleats 29 nailed thereto. In Fig. 4, wide T-beams 30 support the floor and the head of the beam is too wide on one side to permit the ends of the pan forms 28 to be supported by cleats nailed to the beam forms. Where cleats cannot be used, a strip 31 may be nailed beneath the soffit members 14, and the ends of the pan forms supported upon blocks 32 which rest on the strip 31. By knocking off the cleats 29 the pan forms 28 may be lowered without disturbing the beam forms, soffit members or supporting posts.

The construction shown in Figs. 7 and 8 is similar to that shown in Figs. 4, 5 and 6, except that wedges 33 are used for supporting the adjacent ends of the pan forms 28 at the middle joist 20, and blocks 34 are used for supporting the corners of the pan forms upon the stringers 16. By knocking out the wedges 33 the ends of the pan forms 28 supported thereby may be lowered and the pan forms slipped out from under the floor without disturbing any other portions of the forms or supports. Hence the blocks 34 which support the ends of the pan forms 28 may also support the soffit boards 35 beneath the end cross ribs 36. In the construction shown in Figs. 7 and 8 the soffit members 37 are joists arranged on edge with boards 38 along their tops for supporting the ribs 11. This wedge arrangement permits of readily adjusting the height of the pan forms to suit the depth of rib desired. The arrangement shown and described of supporting posts 17 and struts 21, and beam 16, stringers, and joists carried thereby, provides a clear floor space beneath the floor being erected, permitting the workmen to lower and remove the pan forms without trouble, and taking the weight of the floor

under construction off from the lower floors 61 by transmitting it directly to the walls, beams and columns.

It is obvious that changes in the forms and manner of supporting them may be made without departing from the invention. 70

I claim the following as my invention:

1. Centering for concrete floors comprising beam forms and rows of posts beneath said beam forms for supporting them, joists parallel to said beam forms and rows of 75 inclined struts for supporting said joists, the lower ends of said struts being positioned adjacent to the rows of posts with the space between them unobstructed by the centering, and floor forms removably supported on said beam forms and joists.

2. Centering for concrete floors comprising beam forms and rows of posts beneath said beam forms for supporting them, joists parallel to said beam forms and rows of 85 inclined struts for supporting said joists, the lower ends of said struts being positioned adjacent to the row of posts with the space between them unobstructed by the centering, wedges under said struts for supporting them, and floor forms supported on said beam forms and joists.

3. Centering for ribbed concrete floors comprising soffit members adapted to support the ribs of said floors, pan forms arranged between said soffit members, removable supports for said pan forms positioned near the ends of said pan forms, said removable supports being adjustable vertically to adjust the height of said pan forms 100 relatively to said soffit members, joists for supporting said soffit forms, and inclined struts for supporting the joists with the space between them unobstructed by the centering.

4. Centering for ribbed concrete floors comprising beam forms and rows of posts beneath said beam forms for supporting them, soffit members extending from beam form to beam form and supported at their 110 ends on said beam forms and adapted to support the ribs of said floors, joists parallel to said beam forms at the middle of said soffit members for supporting said soffit members, inclined struts for supporting said joists, the lower ends of said struts being positioned adjacent to the rows of posts with the space between them unobstructed by the centering, pan forms arranged between said soffit members, and end supports 115 for said pan forms, said end supports being removably secured in place whereby said forms may be lowered relatively to said soffit members.

5. Centering for ribbed concrete floors 125 comprising inverted pan shape forms having sloping side walls, said pan forms being rigid and spanning substantially one-

half of the floor span, soffit members between the lower edges of said pans, said soffit members being rigid and extending from side to side of the floor span, supports for said soffit members at the ends and middle thereof, the adjacent ends of said pan forms being supported on center supports and the opposite ends of said pan

forms being supported by the same means which supports the ends of said soffit members, whereby upon lowering said center supports, said pan forms can be removed and said soffit members retained in place. 10

Signed at St. Louis, Missouri, this ninth day of November, 1916.

ARTHUR J. WIDMER.
